(Cl. D58—8)

To all whom it may concern:

Be it known that I, Jean Pierre Guerlain, a citizen of France, residing at 47 Avenue Hoche, Paris, France, have invented a new, original, and ornamental Design for a Bottle or the like, of which the following is a specification, reference being had to the accompanying drawing, forming a part thereof.

Fig. 1 is a top plan view of a bottle or the like, showing my new design;

Fig. 2 is a front elevational view of the bottle or the like illustrated in Fig. 1; and

Fig. 3 is a side elevational view of the bottle or the like illustrated in Fig. 1.

I claim:

The ornamental design for a bottle or the like, substantially as shown.
